INVENTOR
BY *Tokuaburo Sato*
B. Amey ATTORNEY

UNITED STATES PATENT OFFICE.

TOKUSABURO SATO, OF OSAKA, JAPAN.

COMPLETE-COMBUSTION APPARATUS FOR MARINE BOILERS.

Application filed January 6, 1922. Serial No. 527,512.

To all whom it may concern:

Be it known that I, TOKUSABURO SATO, a subject of the Emperor of Japan, and a resident of No. 1061 Tamade-Machi, Nishinari-Gun, Osaka, Empire of Japan, have invented new and useful Improvements in Complete-Combustion Apparatus for Marine Boilers, of which the following is a specification.

- 10 This invention relates to combustion apparatus for marine boiler in which a refractory wall is secured on a fire bridge in intimate relation with the flue plate and is provided with an air duct in the mass of said wall which duct is opened to an internal flame passage of the wall at each side for discharging the hot air, preferably, intensively heated air therefrom, sucked in from the underside of the fire bridge, said 20 wall also being extended to form a conical shaped flame guide having a sharp edge at rear end thereof.

This invention has for its purpose to provide a means to make economically complete combustion of fuel in a simple and efficient manner.

My invention will be readily understood by reference to accompanying drawing, in which:

30 Fig. 1 is a longitudinal vertical sectional view of a marine boiler provided with my invention,

Fig. 2 is a cross sectional view of Fig. 1,

Fig. 3 is an enlarged longitudinal sectional detail view of my invention, and

35 Fig. 4 is a cross section thereof, halfly being omitted.

Referring to the drawing, (1) is a marine boiler proper, (2) represents the smoke tubes and (4) is a fire bridge on which the rear end of the fire grate (3) is supported. In the flue and on the fire bridge, a refractory wall (5) is secured in intimate relation therewith, which has a flue opening (5a), the rear end of which is contracted to form a flame guide (6) around the circumference of which is a sharp edge as shown. (7) is fire bridge supporting frame. In the lower side of said fire bridge is a vent hole (8) in which the air is sucked from the ash pit below the grate and is conducted to air ducts (9) provided in the mass of the refractory wall itself. The duct 9 is also opened to the internal flame passage or flue

opening of the wall (5) at the ends as at (10) at points slightly higher than the center of the passage, at each side causing movements so as to eject the heated air into the flame, thus causing practically complete combustion without smoke. In the frame (7), an air regulating box or damper (11) which is open at the top is slidably mounted for regulating the quantity of air passing through the box by any appropriate means, say, by a handle (12) attached to said box.

In this invention, the refractory wall is heated by flame gas from the fire box while the air sucked in from the underside of the fire bridge through the vent hole (8) and the air regulating means (11) becomes brightly heated during its passage through the ducts 9 of said heated wall and is discharged through the jet hole (10) at each side, into the flue opening or flame guide 6. Then, the flame gas is prevented from cooling down up to the ignition temperature of the carbon monoxide. The flame is also prevented from directly rising up from the passage to the smoke tube (2) by means of the flame guide (6), thus making a mixture of the incompletely burned gas and oxygen and providing a greatly promoted combustion. The flame guide (6) is extended, as shown, to form sharp edge which, being extensively heated, serves to highly heat the mixture with the carbon monoxide and oxygen.

My invention is provided to regulate the quantity of the heated air by adjusting the regulating box.

Having now described and ascertained the nature of this invention and in what manner the same is to be performed, I declare that what I claim is:

In a furnace, a fire box, an ash pit, a bridge wall in rear of the ash pit and fire box and having an opening extending rearwardly from the fire box, and a combustion chamber into which said opening discharges, the said bridge wall having on its rear side a flange which depends therefrom and also presents a frusto-conical inner side forming a contraction of the rear end of said opening, the said bridge wall also having a hot air intake opening leading from the ash pit and a duct leading from said hot air intake opening formed in the mass of the bridge wall and discharging into one side of the

first named opening therein and a frame supporting said bridge wall and against the rear side of which the said depending flange of the fire wall bears, said frame and flange 5 also having an opening to establish direct communication between the ash pit and the combustion chamber, and means to control the passage of air through said opening and

also through said hot air intake opening and said duct.

In testimony whereof I affix my signature in presence of two witnesses.

TOKUSABURO SATO.
